UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER-MOTION FOR LOOMS.

1,328,907.

Specification of Letters Patent.

Patented Jan. 27, 1920.

Application filed August 8, 1917. Serial No. 185,156.

To all whom it may concern:

Be it known that I, EDWARD S. STIMPSON, a citizen of the United States, residing at Hopedale, county of Worcester, and State of Massachusetts, have invented an Improvement in Feeler-Motions for Looms, of which the following description, in connection with the accompanying drawings, is a specification, like characters on the drawings representing like parts.

The invention to be hereinafter described relates to feeler motions for looms whereby, when the filling in the active shuttle becomes substantially but not quite exhausted, a train of mechanism is set in operation to effect a change in the condition of the loom. This change may cause replenishment of filling, either by changing the filling carrier or bobbin in the shuttle for one provided with a fresh supply of filling, or by substituting a shuttle with a fresh supply of filling for the one in which substantial exhaustion has been reached.

In feeler motions of the side swipe type, the feeler enters the shuttle on each detecting beat of the lay and ascertains the condition of the filling. Should it find the filling substantially exhausted, movement is imparted to the feeler in a direction longitudinally of the shuttle or bobbin, and this movement is utilized to initiate filling replenishment or effect a fresh supply when the shuttle reaches the replenishing side of the loom. In one form of the side swipe feeler, movement longitudinally of the shuttle or bobbin is effected by the forward push upon the feeler when the filling is substantially exhausted on a detecting beat, and, in another form, means are provided which, independently of the forward push, acts upon the feeler tending to move it longitudinally of the shuttle or bobbin. In the second form of side swipe feeler motions, it is desirable that the feeler shall not be subjected to the action of the side swipe moving means except at the critical period when detecting action is desired on the detecting beat, and an important feature of the present invention consists of a feeler adapted to be moved forwardly on a detecting beat and means rendered effective by such forward movement of the feeler to move the latter in a direction longitudinally of the shuttle when the filling is substantially exhausted.

This feature of the present invention is carried into effect in the present instance by a yielding member having a portion to act upon the feeler as it moves forwardly and cause feeler movement longitudinally of the shuttle, should the filling be substantially exhausted, but adapted to be moved from operative position by forward movement of the feeler when a working supply of filling is present.

It is frequently desirable to operate the loom for a number of picks without laying filling in the shed, or in other words, without using the shuttle. Under such conditions, it is also desirable that the feeler shall not call for a change of filling, when, on a detecting beat of the lay, it fails to find a working supply in the shuttle-box. Another feature of the present invention, therefore, consists in means for moving the feeler in a direction longitudinally of the shuttle dependent for its action upon forward movement of the feeler.

Other important features of the invention in addition to those stated, as well as novel combinations of parts, will be hereinafter described in connection with the accompanying drawings showing a simple and efficient practical embodiment of the invention, it being understood that the invention is not restricted to the particular means and details illustrated and described, but may be variously changed within the true scope thereof as defined by the claims.

In the drawings:—

Figure 1 is a perspective view of sufficient portions of a loom containing the present invention to make clear the construction and operation thereof;

Fig. 2 is a plan view showing the feeler and the action of parts when a working supply of filling is present in the shuttle on a detecting beat;

Fig. 3 is a view similar to that of Fig. 2, but showing the parts in another position when, on a detecting beat, the filling has become substantially exhausted;

Fig. 4 is an under detail view of a portion of the feeler stand, some of the parts being broken away; and

Fig. 5 is a detail in elevation, showing the member for imparting lateral movement to the feeler when the filling is substantially exhausted.

The loom frame may be any preferred

character, and is herein shown as provided with a shipper stand 2 having the usual slot 3 for the shipper 4.

Mounted in suitable bearings 5 appropriately secured to the loom frame or breast beam as at 6, is the change or rock shaft 7, Fig. 1, to which is connected the arm 8 having pivotally secured thereto at 9 the rearwardly-projecting arm 10, which may be 10 appropriately designated for purposes of identification, as the actuator, because, by forward movement of the arm 10 under the conditions to be hereinafter described, filling replenishment is initiated.

15 The feeler or feeler member is appropriately mounted to enter and feel for the filling in the shuttle on each detecting beat of the lay and is mounted for movement toward and from the front of the loom, and 20 also laterally or in a direction longitudinally of the shuttle. To carry out these characteristic features of the feeler, various means may be employed for properly supporting it, but in the present instance of 25 the invention, the feeler stand 11 is provided with a slot 12 through which passes a securing bolt 13 whereby the feeler stand 11 may be adjustably secured in proper position on an appropriate part of the loom- 30 supporting frame. The feeler stand 11 is provided with a slot 14, the rear end portion of which is preferably inclined as at 15 for the purpose of directing the feeler to proper feeling position when it returns 35 rearwardly after having been displaced laterally on a detecting beat, all of which will more fully appear.

The feeler or feeler member 16 may be variously contrived, but in the present instance of the invention, it is formed tubular and provided with a filling-engaging portion 17 having teeth or a roughened face 18 of a character to engage the filling in the shuttle and be held by such filling from 40 movement laterally when a proper or working supply of filling is present. The feeler 16 extends forwardly through a suitable bearing 19 formed on the feeler stand. In the present instance of the invention, this 45 bearing is preferably formed by a part cast integral with the feeler stand 11 and a cap-piece 20, a loose bearing being formed between the parts 19 and 20 to accommodate free movement of the feeler 16 toward and 50 from the front of the loom and also permit it to swing or move laterally under conditions as will presently appear.

Secured to the feeler 16 is a lug 21 through which the feeler may appropriately 55 pass and projecting from each side of the lug 21 are the wing or bearing portions 22 which rest upon the top surface of the feeler stand 11 as the feeler moves lengthwise toward and from the front of the loom. Interposed between the lug 21 and the front

bearing 19, 20 for the feeler is a spring 23 which normally acts to hold the feeler in its rearward position, substantially as indicated by Fig. 1, but is capable of yielding to permit the feeler to move forwardly. 70

Mounted for lateral movement relative to the feeler stand 11 is the slide 24 through which the feeler 16 loosely passes, as best indicated in Figs. 2 and 3. The slide 24 may be supported for sliding movement 75 laterally of the feeler stand 11 in any appropriate manner, but in the present instance of the invention, the feeler stand has rising therefrom the lugs 25 between which the slide 24 is received and a cap-piece 26 80 secured to the lugs 25 maintains the slide 24 in proper position between its guides. In order that the feeler 16 may have appropriate movement with the slide 24, the lugs 25 are slotted at 27, Figs. 2 and 3. An appropriate and convenient way of securing the cap-piece 26 to the lugs 25 is by screw-bolt 28 and if desired, the cap 26 may have a projecting end portion 29 to overlie the end 30 of the slide 24, Fig. 1. 85

Extending downwardly from the lug 21 and entering the slot 14 of the feeler stand is the projection 31 which is adapted to engage the incline or cam portion 15 at the rear portion of the slot 14 under the impulse of the feeler spring 23, the construction being such that when the feeler 16 is free to move rearwardly, the spring 23 acting against the lug 21, will move the feeler into its rearward position, the projection 31 95 at such time riding into the contracted portion of the slot 14 and moving the feeler laterally, if necessary, into proper feeling position. The wings or extensions 22 of the lug 21 are of sufficient extent to ride 100 upon the top surface of the feeler stand 11 when the feeler is moved forwardly and laterally.

The present invention contemplates that the means for giving the feeler its lateral or side swipe movement in a direction longitudinally of the shuttle shall be active only when the feeler is moved forwardly on a detecting beat; and to this end, the present invention provides an arm having a cam 110 portion or incline such that as the feeler moves forwardly on a detecting beat, the arm will act upon the feeler due to such forward movement thereof and if the filling is substantially exhausted at such time, 115 cause the feeler to move longitudinally of the shuttle; but should sufficient filling remain in the shuttle to constitute what may be termed a working supply, the roughened or toothed face of the feeler will sink into 120 the filling and hold the feeler from side swipe movement longitudinally of the shuttle by the arm as the feeler moves forwardly.

In the present instance the means for 130

giving the feeler its side swipe movement longitudinally of the shuttle comprises an arm 32 yieldingly held with its inclined portion 33 in the path of a pin 34 movable with 5 the feeler. In the present instance the pin 34 is secured to one of the wings 22 of the lug 21.

The arm 32 and its yielding character may be variously contrived, but in the present 10 instance of the invention, it is shown as one end of a coil spring 35 supported by a stud or screw-bolt 36 extending from a support 37 secured to the feeler stand. The screw-bolt or stud 36 has a cap-piece 38 provided with a lug 39 adapted to engage the end 40 of the coil spring 35 and a clamping nut 41 serves to maintain the screw-bolt or stud 36 securely locked from rotative movement. The free end of the spring arm 32 in 15 the present instance of the invention, rests against the side of one of the lugs 25 constituting the guides for the slide 24, and the incline or cam portion 33 is disposed frontwardly and in the path of the pin 34, the 20 construction being such that when the feeler is moved frontwardly on a detecting beat, the pin 34 will ride along the incline or cam portion 33 of the yielding arm 32, and if filling be substantially exhausted at such 25 time, the feeler will be moved laterally or in a direction longitudinally of the shuttle as it moves frontwardly; but should a working supply of filling yet remain in the shuttle, the toothed or roughened face of the 30 feeler will sink into the filling and prevent lateral movement of the feeler longitudinally of the shuttle so that as the feeler moves frontwardly, the arm 32 is itself moved laterally by the feeler.

40 The end 30 of the slide 24 is provided with an opening to receive the end of a connector 42 joining the slide and the filling replenishing controlling means. The overhanging portion 29 of the cap 26 serves to 45 prevent disengagement of the connector 42 from the slide. Any preferred means may be operated by the rod 42 to initiate replenishment of filling, and the invention is not limited in this respect; but in the present 50 instance, the rod 42 is shown as connected at 43 to a bell crank lever 44 pivoted at 45 and having its end 46 underlying the actuator 10, the construction being such that should the yielding arm 32 cause side swipe 55 movement of the feeler as it moves frontwardly on a detecting beat, the bell crank lever 44 would be turned contraclockwise, Fig. 1, and lift the end of the actuator 10 into the path of an operating member 47 which in the present instance of the invention 60 is shown as a part actuated from the weft hammer or cam follower.

From the construction described as one good form or embodiment of the present 65 invention, it will be noted that the means

for moving the feeler laterally or longitudinally of the shuttle is dependent for its operative function upon the frontward movement of the feeler; and that when the feeler is in its rearward or feeling position 70 it may not be under the stress of said means. Under such circumstances, the spring 23 and the incline 15 coöperating with the projection 31 of the feeler lug 21 may be sufficient to return the feeler to rearward feeling 75 position after a replenishing operation. It may be desirable at times, however, to make sure that the feeler is drawn laterally back to its feeling position after a replenishing operation, and this will be desirable where 80 the spring arm or member 32 engages the feeler pin 31 earlier in the feeler's frontward movement. To this end the actuator 10 may be provided with an incline portion 85 48 which, as the actuator 10 is moved frontwardly by the operating member 47, after a call for replenishment, will ride over the end 46 of the bell crank and pull the feeler 16 back to its proper lateral feeling position, so that as the lay retreats, the spring 23 90 may unerringly place the feeler in its correct rearward feeling position.

By proper relation of the yielding arm 32 and its incline 33 and the feeler pin 34, it is evident that the time of action of the 95 arm 32 to impart the side swipe movement to the feeler may be made earlier or later in the detecting beat. This is of importance in some cases, especially where the spring 23 is light and it is desirable to give the 100 end of the feeler time to sink into the filling before the side swipe operating means comes into play. This change in the time of action of the side swipe operating means may readily be effected by changing the 105 position of the incline or cam portion 33. This may be done by placing the cam portion 33 nearer to or farther from the end of the arm 22.

In the illustrated form of the invention, 110 the end of the actuator 10 is shown as provided with a shoulder 49, a recess 50 and a shouldered portion 51 coöperating with the head 52 of the operating member 47, and if desired, these parts may all be the same as 115 fully described in the prior application Serial Number 147,468, filed February 8, 1917, but the present invention is, of course, not restricted to these details.

In Fig. 1 the shuttle 53 is shown provided 120 with a bobbin or filling carrier provided with the filling 54, and in order that the feeler may properly enter and feel for the filling in the shuttle, the front wall 55 of the shuttle-box and the front wall 56 of the 125 shuttle when in the detecting box, are slotted as indicated at 57.

In Fig. 2, the action of the parts is represented when on a detecting beat the feeler finds a working supply of filling present in 130

the shuttle, and it will be noted that the pin 34 as it rides along the cam or incline 1 portion 33, effects movement of the arm 32 into inoperative position; whereas in Fig. 3 5 it will be noted that the feeler detects substantial exhaustion of the filling so that as the pin 34 travels along the incline 33 of the arm 32, the feeler is moved laterally in a direction longitudinally of the shuttle, 10 and the actuator 10 is, through the intermediate connections, placed in operative relation with the operating member 47, whereby filling replenishment is initiated. It will be noted that when the feeler is in its feeling 15 or rearward position, the member 32 does not bear against the feeler and only after the feeler has been moved forwardly to a predetermined point, thereby causing its spring 23 to exert its substantially maximum rearward pressure, does the member 20 32 start to act. The consequence is that the spring 23 may be made light and yet cause good holding contact between the feeler and filling before the effect of the laterally moving force is brought into action. 25

What is claimed is:—

1. In a feeler motion for looms, the combination of the lay and shuttle-boxes, a filling feeler adapted to enter the shuttle and 30 be moved forwardly on a detecting beat, means with respect to which the feeler reciprocates on each detecting beat and positioned to act upon the side of the feeler as it moves forwardly relative to said means 35 to impart movement thereto longitudinally of the shuttle when the filling is substantially exhausted and adapted to be moved from its actuating position by the feeler as it moves forwardly when a working 40 supply of filling is present.

2. In a feeler motion for looms, the combination of a feeler mounted for movement toward and from the front of the loom and longitudinally of the shuttle, mechanism 45 positioned by longitudinal movement of the feeler to initiate replenishment of filling, a yielding cam device adapted to act upon the feeler as it moves forwardly to impart feeler movement longitudinally of the shuttle when the filling is substantially exhausted and to be moved from operative position by forward movement of the feeler when a working supply of filling is present. 50

3. In a feeler motion for looms, a feeler stand, a feeler mounted for reciprocating and lateral movements on said stand, means normally disconnected from the feeler and adapted to be engaged thereby when the feeler is moved forwardly to effect lateral 55 movement of the feeler should the filling be substantially exhausted on a detecting beat.

4. In a filling feeler mechanism for looms, the combination of the lay, a shuttle, a filling carrier, and a filling feeler mechanism comprising a filling feeler mounted 60

for movement toward and from the front of the loom, means for holding the feeler in rearward feeling position and permitting forward movement of the feeler, and a laterally movable yielding member having 70 a portion adapted to move the filling engaging end of the feeler lengthwise of the shuttle provided the filling is substantially exhausted on a detecting beat and to effect lateral displacing movement of said member 75 by the forward movement of the feeler should a working supply of filling be present.

5. In a filling feeler mechanism for looms, the combination of a filling feeler mounted for movement toward and from the front of 80 the loom and to permit the filling engaging end to move longitudinally of the shuttle, a yielding member having a cam portion for moving the end of the feeler longitudinally of the shuttle when the filling is substantially exhausted on a detecting beat and effecting movement of the yielding member away from normal position when the end of the feeler is held from movement longitudinally of the shuttle by the filling, and 85 means positioned by movement of the end of the feeler longitudinally of the shuttle for operating the filling supply controlling means. 90

6. In a loom, the combination of a feeler 95 mounted for lengthwise and lateral movements, and a spring having a deflected portion for giving the feeler lateral movement as it is moved lengthwise and adapted to yield when the feeler is held from lateral 100 movement as it is moved lengthwise.

7. In a loom, the combination of a feeler mounted for lengthwise and lateral movements, an arm having a cam portion adapted to act upon the feeler as it is moved 105 lengthwise toward the front of the loom to impart lateral movement to the feeler, and means for supporting the arm to permit lateral movement thereof when lateral movement of the feeler is obstructed as it is 110 moved forwardly.

8. In a loom, the combination of a feeler mounted for lengthwise and lateral movements, filling supply controlling means operatively connected to the feeler, an arm 115 having a cam portion adapted to act upon the feeler as it is moved lengthwise toward the front of the loom to impart lateral movement to the feeler, and means for supporting the arm to permit lateral movement thereof 120 when lateral movement of the feeler is obstructed as it is moved forwardly.

9. In filling feeler mechanism, the combination of a filling feeler mounted for movement toward and from the front of the 125 loom and to permit its filling engaging end to move longitudinally of the shuttle, filling supply controlling means, and an arm having a cam portion extending into the path of and engaging a part of the feeler 130

as it moves frontwardly and adapted to move the filling engaging end of the feeler longitudinally of the shuttle, said arm being mounted to permit movement thereof to one side as the part of the feeler passes along the cam portion.

10. In a feeler motion for looms, a feeler stand, a feeler mounted for reciprocating and lateral movements on said stand, means normally disconnected from the feeler when it is in feeling position and adapted to be engaged by the feeler when it has been moved frontwardly to a predetermined point to effect lateral movement of the feeler provided the filling is substantially exhausted on a detecting beat.

11. In a feeler motion for looms, the combination of a feeler mounted for movements laterally and toward and from the front of the loom, and a spring having a deflected

portion for imparting such lateral movement only after the feeler has been moved frontwardly to a predetermined point provided the filling is substantially exhausted on a detecting beat.

12. In a feeler motion for looms, the combination of a feeler mounted for movements laterally and toward and from the front of the loom, and a spring along which the feeler moves but that is ineffectual to cause such lateral movement when the feeler is in rearward position and rendered effective when the feeler has been moved frontwardly to a predetermined extent to cause such lateral movement provided the filling is substantially exhausted on a detecting beat.

In testimony whereof, I have signed my name to this specification.

EDWARD S. STIMPSON.
